CLAIM

The ornamental design for a kettle, as shown and described.

DESCRIPTION

FIG. 1 is a front-right-top perspective view of a kettle, showing my new design;

FIG. 2 is a front elevational view thereof (the rear elevational view being a mirror image thereof);

FIG. 3 is a left side elevational view thereof;

FIG. 4 is a right side elevational view thereof;

FIG. 5 is a top plan view thereof; and,

FIG. 6 is a bottom plan view thereof.
